UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,246,553.

Specification of Letters Patent. Patented Nov. 13, 1917.

Application filed September 14, 1915. Serial No. 50,559.

To all whom it may concern:

Be it known that I, CORNELIUS B. CORCORAN, a citizen of the United States, residing in borough of Bronx, in the county of Bronx, 5 city and State of New York, have invented certain new and useful Improvements in Type-Writing Machines, of which the following is a specification.

The present invention relates to card-holding devices for typewriting machines. More particularly, the invention relates to mechanism for setting the card-holder for the release of a card which has been typewritten, and for the reception of a card to be 15 typewritten. The invention also relates to mechanism for determining the movement to be given the card-holder in positioning the card for writing the first line at a selected place thereon.

20 The invention is especially applicable to a card-holder of the character set forth in the patent to John C. McLaughlin, No. 1,070,279, dated August 12, 1913. The card-holder of that patent comprises a blade carried in a 25 recess in the body of the platen, and shiftable therein by means of a rock-shaft, to which it is connected. The rock-shaft is also carried within the platen, and has fixed thereto, beyond the end of the platen, a finger-piece or key by means of which it is rocked. When the rock-shaft is turned in one direction, the blade is shifted to project 30 a lip or jaw, on the outer edge thereof, beyond the face of the platen, so that a card 35 may be inserted between the jaw and the platen; whereupon, in release of the key, a spring retracts the blade to cause the jaw to clamp the edge of the card against the face of the platen. With the card so clamped, 40 the platen is turned to present the proper part thereof to the printing point of the machine. The card, when printed, is released by again shifting the jaw outward; and, if no new card is inserted, the spring retracts 45 the blade until the jaw thereof is flush with the face of the platen, so that the machine may then be used for ordinary correspondence. In the patent referred to, the outward shift of the blade, for the release or reception 50 of a card, is effected manually.

It is an object of the present invention automatically to effect the throw of the clamp to card-releasing and receiving position by mere rotation of the platen a sufficient degree in line-space direction. For

this purpose, in the preferred form of the invention, there is provided a detent, pin, or other device on the frame of the machine, in the path of the key which operates the clamp; so that, upon sufficient rotation of 60 the platen, the key strikes the device on the frame, and is actuated thereby to throw the clamp as if operated manually. Reverse movement of the platen removes the key from its actuating device and permits retraction of the clamp to card-holding position, or to the position in which it lies when the machine is used for ordinary correspondence. The clamp is preferably operable manually as well as automatically. 70

It is a further object of the invention to provide means for automatically arresting the platen after it has been rotated with a newly inserted card a sufficient distance to bring a given place on the card to the printing point for the printing of the first line. It is also an object of the invention to make this movement of the platen with the card, variable; so that, according to the length of card, or other conditions, the distance from the top of the card to the first line of writing thereon may be varied at will. In the preferred form of the invention, after the card to be typewritten has been clamped, as aforesaid, the platen is 75 turned in counter line-feed direction until a stop on the end of the platen strikes a pin set into a plate on the platen frame. This pin arrests the platen with the card in position for the printing of the first line thereon. In order that the reverse throw of the platen and resultant position of the first line of printing may be varied, the position of the pin on its support is variable; and, to 80 this end, the pin may be set into any one of 85 a series of holes in the pin support, the holes being preferably arranged in the arc of a circle concentric with the platen axis. 90

Another object of the invention is to have the automatic clamp-operating and card-positioning devices of such nature and mounting that the same may form a permanent part of the typewriting machine, and be effective, or not, according to whether cards are to be written or the machine is to 100 be used for ordinary purposes; and it is a feature of the invention that the machine may at any time be quickly set by the operator for one or the other of these uses without the use of tools, or other inconvenience. 105 110

To silence the card-holder, and to permit of indefinite movement of the platen in line-space or reverse direction, the card-positioning stop and key-operating device on the frame are preferably mounted on a plate which is shiftable on the platen frame between a position in which these devices are effective and another position in which they are out of reach of their coöperating parts on the platen, and are ineffective.

Other features and advantages will hereinafter appear.

In the accompanying drawings,

Figure 1 is a perspective view, partly broken, of the platen and platen frame of an Underwood typewriting machine, having the present invention applied thereto.

Fig. 2 is a view in right hand end elevation of the assembled apparatus shown in Fig. 1, the stop-carrying plate being broken away to show the parts behind the same, and the platen, with a card thereon, being shown in position for printing the first line on the card.

Fig. 3 is a view similar to that of Fig. 2, except the platen is shown with the clamp in card-releasing and receiving position.

Fig. 4 is a view in right hand end elevation of the apparatus shown in Fig. 1, the stop-carrying plate being set back for ordinary writing, so that the stops are ineffective.

The platen 10 is of the hollow kind, having an inner shell 12 of wood or other suitable material, and an outer body 13 of material to serve as the printing surface. The platen has end plates 14 by means of which it is secured to and supported on an axle 15 journaled in the end plates 16 of the platen frame. At its ends the axle carries the usual hand wheels 17 and line-space ratchet wheel 18. The latter is operated as in the Underwood machine by means of a pawl 19 on a slide 20 on the end plate 16 of the platen frame. The slide is actuated by a bell crank finger-lever 21 pivoted at 22 to the platen frame; the arm 23 of the lever being adapted to engage and throw back the slide 20 when the finger piece 24 is moved to the right. A spring 25 attached to the slide and to the plate 4 returns the pawl after each line-space feed. The usual paper guide 26 and table 26^a are shown, as are also the usual feed rollers 27 and 27^a.

As is described in United States Letters Patent, No. 1,070,279, to John C. McLaughlin, dated August 12, 1913, the platen has alined slots 28 within which a card-holding blade or clamp 29 is set. The uncut portion 30 between the slots prevents warping of the platen, such as might occur if there were one continuous slot. The blade 29 is cut at 31 to clear the body of the platen at 30, and is cut away at 32, at its ends, for the same reason. The blade is shown as of a width

to move easily in the slots, while nevertheless practically closing the slots to the admission of dust; and forming with the face of the platen a continuous printing surface when the blade is retracted (see Fig. 4).

The blade is grooved at 33 to receive the card. It is adapted to be thrown out to Fig. 1 and Fig. 3 position to receive the card, and to be slightly retracted from Fig. 3 to Fig. 2 position to clamp the card between its lip or jaw 34 and the face of the platen. The clamp except when in use is held in Fig. 4 position, with its outer edge flush with the face of the platen, so that the platen may be used in the usual way for ordinary writing. In this position the blade may bear at its inner edge against the axle of the platen to present an unyielding printing surface at its outer edge. For actuating the blade 29 there is, journaled in the platen end-plates 14, a rock-shaft 35 having fast thereto a pair of arms 36 having hooked ends, which pass through slots 37 in the blade 29. Sufficient looseness is allowed between the arms and the blade to allow the arms to be rocked by the shaft 35 without binding of the blade. A coil spring 38, attached at one end to one of the arms 36, and at its other to a pin (not shown) on the inner face of the adjacent plate 14 tends to turn the arms 36 and shaft 35 in a direction to retract the clamping blade into the platen, and to hold the same normally in Fig. 4 position.

Whenever desired, the blade may be thrown out, to receive, or to release a card, by means of a finger piece or key 39, fast to the rock-shaft 35, beyond the end of the platen. To facilitate the operation of the finger piece 39, there is fast to the adjacent end plate 14, another finger piece 40; so that, by seizing the finger pieces between the fingers and pressing the fingers together, the finger piece 39, and with it the shaft 35, is rocked against the action of the spring 38, to project the blade. This pressure is maintained until the card is inserted (see Fig. 3), whereupon the fingers are removed, and the spring 38 retracts the blade until the card is clamped as shown in Fig. 2. At any time the blade may be projected in like manner to release the card, and if no card is in place, then upon release of the finger piece, the blade moves to Fig. 4 position.

The printed card is ejected by movement of the platen in line-feed direction, and, in order that the key 39 may operate automatically to release the card when the platen is turned to eject the same, there is provided a clamp release pin 41 on a plate 42, secured to the right hand end-plate 16 of the platen frame. This pin projects into the path of the key 39, so that, if the platen be turned forward sufficiently, the key will strike the pin 41 (see Figs. 1 and 130

3), and by the latter will be rocked, as hereinbefore described, to project the blade to Fig. 3 position. While the platen is in this position, the printed card is removed and a blank card substituted therefor. The platen is then turned backward to bring the new card to printing position. At the commencement of this backward movement of the platen, the key 39 withdraws from the pin 41, allowing the spring 38 to retract the blade to clamp the card.

For automatically deterring the movement of the platen to bring the newly inserted card to position for printing the first line thereon, the plate 42, which carries the pin 41, also carries a stop pin 43. The pin 43 projects into the path of the fixed finger piece 40 (see Fig. 2), so that, upon requisite backward movement of the platen, the finger 40 strikes the pin 43 to arrest the platen. It is desirable that the position of the first line of printing be variable at the pleasure of the operator, whether to adapt the apparatus to cards of different length, or for other reasons. Accordingly the pin 43 is threaded to be set into any one of a number of tapped holes 44 in the plate 42. The holes 44 are arranged in the arc of a circle concentric with the axle of the platen, and are spaced apart the distance between successive teeth on the line-space wheel 18. Thus, by positioning the pin 43 higher or lower in the pin-hole arc, the position for the first line of print is made lower or higher on the card.

So that the machine may be readily adapted to use for general correspondence and for other work which involves complete rotation of the platen, the plate 42 is shiftable to remove the pins thereon from the path of the fingers 39 and 40. A flange 45 on the plate, by means of which the plate is secured to the platen frame-piece 16, has two slots 46 and 47 therein. A screw 48 passes through the slot 46 and has a head, which, while preventing the plate from lifting, does not prevent sliding movement of the plate on the platen frame. A thumb screw 49 passes through the slot 47 into the platen frame, and the head thereof is adapted to be turned down against the plate 42 to prevent both sliding and lifting of the plate. The thumb screw 49 may however be loosened at will to allow the plate 42 to be slid from Fig. 1 position to Fig. 4 position, in which latter position, it will be noted, the pin 41 lies inside the path described by the offset ends of the fingers 39 and 40; and the pin 43 lies entirely to the rear and out of reach of these fingers. After being shifted to Fig. 4 position, plate 42 is again secured against accidental displacement by tightening the thumb screw 49. The slots 46 and 47 are of the correct length to limit the throw of the plate in either direction, and to determine the proper setting

of the same in effective and ineffective positions.

It will be observed that in the form of the invention shown in the drawings, the card is both inserted and removed at the front of the machine. In inserting the card, it is passed forward and downward between the platen and the paper fingers 50 until its leading edge enters the groove 33 in the clamp blade, as shown in Fig. 3. The parts are again in Fig. 3 position when a printed card is to be withdrawn, and the withdrawal is effected by merely drawing the card upward from its position between the platen and the paper fingers.

Variations may be resorted to within the scope of the invention, and portions of the improvements may be used without others.

Having thus described my invention, I claim:

1. In a typewriting machine, the combination with a platen frame and a platen rotatably mounted thereon, of a card-holding means, means for determining the position of the platen for the first line of print on the card, and means for releasing the card automatically on rotating the platen to a definite position, both said determining means and said releasing means being movable to positions where they are inoperative, so that said platen may be used for ordinary writing.

2. In a typewriting machine, the combination with a platen frame and a platen rotatably mounted thereon, of a card-holding means, means for adjustably determining the position of the platen for the first line of print for cards of different lengths, and means for releasing the card automatically on rotating the platen to a definite position, both said determining means and said releasing means being movable to inoperative positions, so that the platen may be used for ordinary writing.

3. The combination with a revoluble platen, of a card-holding device connected to the platen, means controlled by the rotation of the platen for automatically moving the card-holding device to card-releasing and receiving position and arresting the platen, and means for moving the card-holding device to said position independently of rotation of the platen.

4. The combination with a revoluble platen having a recess from the printing face to the interior thereof, of a card-holding device within said recess, means for holding said device in position to prevent its protruding beyond the face of the platen, and means for automatically and manually projecting said device beyond the face of the platen, and for arresting the platen when said device is projected automatically.

5. The combination with a revoluble platen having a recess from the printing face to the interior thereof, of a card-holding

ing device slidable in said recess, means automatically operable upon predetermined rotation of the platen in line-space direction to project said device outward in said recess and arrest the platen, and means automatically operable on reverse rotation of the platen for retracting said device into said recess.

6. In a typewriting machine, a platen frame, a revolute platen thereon, means for holding a card to the platen with the leading edge of the card in predetermined position with respect to the position on the platen at which the first line of printing is to be made, means for moving the platen with the card to bring the card to position for the printing of the first line thereon, and a stop on the platen-frame for automatically arresting the platen and card when such movement has been effected, said stop adjustable on the platen-frame into position to render it inoperative.

7. In a typewriting machine, a platen frame, a revolute platen thereon, means for holding a card to the platen with the leading edge of the card in predetermined position with respect to the position on the platen at which the first line of printing is to be made, means for moving the platen with the card to bring the card to position for the printing of the first line thereon, a stop on the platen frame for automatically arresting the platen and card when such movement has been effected, said stop slidably mounted on the platen-frame for movement into and out of operative position, and means to lock the stop in either position.

8. In a typewriting machine, a platen frame, a revolute platen thereon, means for holding a card to the platen with the leading edge of the card in predetermined position with respect to the position on the platen at which the first line of printing is to be made, means for moving the platen with the card to bring the card to position for the printing of the first line thereon, means for automatically arresting the platen and card when such movement has been effected, and means for adjusting said arresting means to advance or retard the action of the same, so that the position of the first line of printing on the card may be varied at will.

9. In a typewriting machine, a platen frame, a revolute platen thereon, means for holding a card to the platen with the leading edge of the card in predetermined position with respect to the position on the platen at which the first line of printing is to be made, means for moving the platen with the card to bring the card to position for the printing of the first line thereon, and a stop on the platen frame for automatically arresting the platen and card when such movement has been effected, said stop being

shiftable from one to another of a number of retaining recesses therefor in the platen frame, so that the position of the first line of printing on the card may be varied at will.

10. In a typewriting machine, a platen frame, a revolute platen thereon, means for holding a card to the platen with the leading edge of the card in predetermined position with respect to the position on the platen at which the first line of printing is to be made, means for moving the platen with the card to bring the card to position for the printing of the first line thereon, and a stop on the platen-frame for automatically arresting the platen and card when such movement has been effected, said stop being shiftable from one to another of a number of retaining recesses therefor arranged on the platen frame in the arc of a circle concentric with the axis of the platen, so that the position of the first line of printing on the card may be varied at will.

11. In a typewriting machine, a platen frame, a revolute platen thereon, means for holding a card to the platen with the leading edge of the card in predetermined position with respect to the position on the platen at which the first line of printing is to be made, means for moving the platen with the card to bring the card to position for printing of the first line thereon, means for automatically arresting the platen and card when such movement has been effected, means for effecting a line-feed of the platen with the card, means for automatically releasing the card from the holder after a predetermined movement thereof in line-feed direction, and means for manually effecting such release at any time.

12. In a typewriting machine, a platen frame, a revolute platen thereon, a card-clamp connected to the platen in normally inoperative position, a key on the platen for throwing open the clamp, a pin adapted to be set in the path of the key to engage and operate the key when rotation of the platen in line-space direction brings the key to the pin, a stop for limiting the movement of the platen in counter line-space direction to determine the position of the first line of print on the card, a plate on which said pin and stop are carried, and means for shifting the plate on the platen frame to a position thereon in which said pin and stop are ineffective.

13. In a typewriting machine, a platen frame, a revolute platen thereon, a card-clamp connected to the platen in normally inoperative position, a key on the platen for throwing open the clamp, a pin adapted to be set in the path of the key to engage and operate the key when rotation of the platen in line-space direction brings the key to the pin, a stop for limiting the movement of the platen in counter line-space direction to de-

termine the position of the first line of print on the card, and means for rendering said pin and stop effective or ineffective at will.

14. In a typewriting machine, a platen frame, a revoluble platen thereon, a card-clamp seated in a recess in the face of the platen in normally inoperative position, a key on the platen for throwing open the clamp, a pin adapted to be set in the path of the key to engage and operate the key when rotation of the platen in line-space direction brings the key to the pin, a stop for limiting the movement of the platen in counter line-space direction to determine the position of the first line of print on the card, and means for rendering said pin and stop effective or ineffective at will.

15. In a typewriting machine, the combination with a rotary platen, of a card-holding device thereon, a stop to arrest the platen when rotated in one direction, with the card-holding device in card-receiving position, means operable automatically as the platen is rotated in the opposite direction away from said stop position to move said card-holding device from said card-receiving position to a position to clamp the card to the platen, and a stop to arrest the platen when it has been rotated a predetermined distance from said card-receiving position, said last-mentioned stop adjustable to vary the position at which the platen is arrested thereby.

16. In a typewriting machine, the combination with a rotary platen, of stops to limit the backward and forward rotation of the platen, a card-holding device mounted on the platen and moved to card-receiving position by the forward stop, and means to automatically actuate said device to clamp the card to the platen as the latter is rotated backwardly from the forward stop position, one of said stops being adjustable to vary the angle through which the platen may be rotated between the stops.

17. In a typewriting machine, the combination with a rotary platen, of stops to limit the backward and forward rotation of the platen, a card-holding device mounted on the platen and moved to card-receiving position by the forward stop, means to automatically actuate said device to clamp the card to the platen as the latter is rotated backwardly from the forward stop position, a support on which said stops are mounted, said support shiftable to move the stops out of position to arrest the platen, whereby an unlimited rotation may be imparted to the platen, and means for locking said support in either position.

18. In a typewriting machine, the combination with a rotary platen, of stops to limit the backward and forward rotation of the platen, a card-holding device mounted on the platen and moved to card-receiving posi-

tion by the forward stop, means to automatically actuate said device to clamp the card to the platen as the latter is rotated backwardly from the forward stop position, a support on which said stops are mounted, 70 said support shiftable to move the stops out of position to arrest the platen, whereby an unlimited rotation may be imparted to the platen, and means for locking said support in either position, one of said stops adjustable on its support to vary the arc through which the platen may be rotated between said stops.

19. In a typewriting machine, the combination with a rotary platen, of a card-holding clamp carried by the platen and extending lengthwise thereof, said clamp slidable into and out of the body of the platen, a stop to arrest the forward rotation of the platen and operable to hold said clamp projected 80 into position to receive the edge of a card placed thereon, means operable automatically as the platen is rotated backwardly from said stop position to move said clamp inwardly to grip the card, a second stop to arrest the platen when it has been rotated backwardly from said first stop position to bring the card into position to receive the first line of writing, a support on which said stops are mounted, said support slidably 95 mounted on the platen-frame for moving the stops into and out of position to arrest the platen, and a clamping screw to clamp said support to the platen frame in either position.

20. In a front-strike typewriting machine, the combination with a rotary platen, of a card-holding clamp carried by the platen and extending lengthwise thereof, said clamp shiftable radially of the platen 105 inward from a projected position for receiving the edge of a card, to a card-clamping position, a stop to arrest the platen when it has been rotated forwardly into position to bring said clamp to the front of the platen, 110 said stop operable to hold the clamp in said card-receiving position, means to automatically shift the clamp to said clamping position as the platen is rotated backwardly from said stop position, a stop to arrest the 115 backward rotation of the platen when the card has been carried to a position to receive the first line of writing, and means whereby said stops may be rendered ineffective so that the platen may have unlimited rotation, said clamp being movable inwardly to a position in which its outer surface is flush with the surface of the platen.

21. In a front-strike typewriting machine, the combination with a rotary platen 125 having a recess lengthwise thereof and extending from the printing face to the interior of the platen, of a card-holding and clamping bar projecting outwardly through said recess, a rock shaft mounted in the 130

platen and having a connection with said bar for shifting the latter inwardly from a card-receiving position to a card-clamping position, a finger-piece on said rock shaft 5 for manually operating the clamping bar, a stop on the platen-frame in the path of said finger-piece to automatically project said bar and to arrest the platen when the latter is rotated forwardly to a predetermined position, and a spring to automatically retract 10 said bar to card-clamping position as the platen is rotated rearwardly from said stop position.

22. In a typewriting machine, the combination with a platen and a platen axle, of a 15

card-receiving blade movable in said platen, said blade in normal position having its outer end flush with the face of the platen, and being of a width equal to the distance from the face of the platen to the axle of the platen, so that when said blade is in normal position, the inner edge thereof bears against the platen axle, so that an unyielding printing surface is presented on the outer edge thereof. 20
